GAME APPARATUS

Application filed December 15, 1928. Serial No. 326,376.

My invention relates to game apparatus, and it has particular reference to game apparatus the playing of which is in simulation of the game of base-ball.

5 It is a purpose of my invention to provide a game apparatus adapted to be played in a manner resembling both the game of base-ball and the well known game of pocket billiards, the results being determined by the 10 skill of the player or players in the projection of an object ball over a playing field by the use of a cue and cue ball as in pocket billiards.

It is also a purpose of my invention to provide 15 a game apparatus in simulation of base-ball where mechanism for scoring is operated automatically through the agency of a playing ball, and also mechanism for advancing base-running player members around the 20 bases of the playing field in accordance with the base value of hits made by the player.

I will describe only one form of game apparatus embodying my invention, and will then point out the novel features thereof in claims.

25 In the accompanying drawing:

Figure 1 is a view showing in top plan one form of game apparatus embodying my invention;

Fig. 2 is a vertical sectional view taken on 30 the line 2—2 of Fig. 1;

Fig. 3 is a longitudinal sectional view taken on the line 3—3 of Fig. 2;

Fig. 4 is a sectional view taken on the line 4—4 of Fig. 1;

Fig. 5 is an enlarged fragmentary vertical sectional view of one of the pockets in the playing field illustrated in Fig. 2 showing in detail the surrounding ball deflecting mechanism as well as the corresponding electrical 40 contacts;

Fig. 6 is an enlarged sectional view of a part of the apparatus as illustrated in Fig. 2 showing one of the edge pockets of the playing field and the belt for advancing the base- 45 running player members around the bases;

Fig. 7 is a view similar to Fig. 6 illustrating the manner in which the corresponding electrical contacts are closed by the playing ball;

50 Fig. 8 is a fragmentary perspective view

illustrating the belt, one of the base-running player members, and the means for moving the member to an inactive position;

Fig. 9 is an enlarged detail perspective view of the scoring mechanism embodied in the apparatus;

Figs. 10, 11, and 12 are views showing the scoring mechanism in side elevation and illustrating the various positions which it occupies during one cycle of operation;

Fig. 13 is an enlarged detail perspective view of the control mechanism for the base-runner advancing belt;

Fig. 14 is a vertical sectional view taken on the line 14—14 of Fig. 13;

Fig. 15 is a vertical sectional view taken on the line 15—15 of Fig. 13;

Fig. 16 is a top plan view of the control mechanism shown in Fig. 13 and illustrating one of the devices thereof in active position;

Fig. 17 is a fragmentary plan view showing one of the control devices in active position and illustrating the manner in which it is operated by advance movement of the belt;

Fig. 18 is a view similar to Fig. 17 showing the control device in retracted or inactive position;

Figs. 19 and 20 are vertical sectional views taken on the lines 19—19 and 20—20, respectively, of Figs. 17 and 18; and

Fig. 21 is a diagrammatic illustration of the electrical circuits for the apparatus.

Playing field

The apparatus in its present embodiment 85 comprises a table including legs L and a top T, the latter comprising a frame 15 of rectangular outline and with its inner edge defining generally the contour of a base-ball playing field. The table top also includes 90 a board 16, the upper surface of which constitutes the playing field, and which surface may be finished to facilitate rolling of the balls thereover and to render such rolling movement noiseless and to prevent injury to 95 the balls. Such a surface may be provided in simulation of the conventional pocket billiard table. The playing field 16 is bounded by a transversely tapered cushion 17 constructed in a manner similar to the cushion 100

of a pocket billiard table for the purpose of securing the desired rebounding movements of the playing balls. In the surface of the playing field, at intervals along the sides and one end thereof, as illustrated in Fig. 1, are a series of pockets or orifices 18 designed for the reception of the playing ball and each having semicircular and countersunk entrances 19 designed to facilitate the entrance of the playing ball into the pocket or orifice. At the further end of the playing field certain of the pockets are separated by a V-shaped cushion 20 which projects into the playing field and provides an abutment against the inclined edges of which the playing ball is adapted to impinge in order to change the direction of movement of the ball over the playing field and to project the ball in the direction of the pockets at the sides of the playing field. Within the surface of the playing field at points spaced from the side and in pockets 18 are other pockets or orifices 21 each of which is provided with a relatively large and circular countersunk entrance 22 which is best illustrated in Fig. 5. Similarly, each pocket 21 is designed to receive the playing ball, the large entrance 22 facilitating passage of the ball into the pocket. I have shown in the present instance four such pockets 21 arranged on the playing field to intercept the playing ball in its movement toward certain of the side pockets 18, thereby increasing the skill necessary to project the ball into those pockets which are productive of hits or runs in the playing of the game.

As a further means for increasing the difficulty in this respect, each pocket 21, or rather the entrance 22 thereof, is surrounded by an annular frame 23 separated for rotative movement by ball-bearings 24 movable in the raceways of an annulus 25. The surface of the board 16 is constructed to receive the frame and annulus and a retaining ring 26 disposed in overlapped relation to a lip 27 of the frame 23 to confine the frame against displacement. This construction is best illustrated in Fig. 5, and as here shown, the upper surface of the frame 23 is inclined in continuation of the inclination of the entrance surface 22 while the ring 26 lies flush with the surface of the playing field in order that movement of the playing ball into the entrance 22 may not be impeded. At intervals about the frame 23 are upstanding arms 28 in each of which is journaled a stub shaft 29 extended into and secured within a ball 30 whereby the ball is mounted for rotation about the shaft 29 as a center. Thus, the several balls 30 are mounted for bodily rotation by the frame 23, and each about its own axis as a center. In the present instance I have shown the balls 30 of such diameter as to have contact with the surface of the playing field 16 in order that when the frame 23 is rotated, the several balls will be rotated individually

about their own axes. Such individual rotation operates in the playing of the game to further deflect the intended projection of the playing ball over the surface of the playing field. It will also be understood that the balls tend to deflect the playing ball into the pockets 21, which operation constitutes an out in the playing of the game, as will be described hereinafter.

Certain of the pockets 18 are designated by the numerals 1^b to 4^b inclusive, to indicate that when the playing ball enters these pockets it constitutes a hit, the base value of which is designated by the numeral. The remaining pockets 18 are designated by the letter S, indicating a strike, and consequently it will be understood that when the playing ball enters any one of these pockets it counts as a strike in the playing of the game. The pockets 21 are designated by the word Out, which is, of course, indicative of the fact that when a ball enters any one of these pockets it constitutes an out in the playing of the game.

In simulation of the base-ball field, the frame 15 of the apparatus is provided with plates 31, 32, 33, and 34, in representation of the four bases of a base-ball diamond. These plates are equidistantly spaced, and are designated by indicia as illustrated in Fig. 4 to indicate the respective bases. Members in representation of base-running players are provided and movably mounted to advance around the bases, as will be described hereinafter.

As best illustrated in Figs. 2, 3, and 5, the pockets or orifices 18 and 21 are in communication with two main runways 35 arranged beneath the board or playing field 16 and provided with branch runways 36 which connect the main runways to the pockets or orifices. The construction and arrangement of these runways is such that balls deposited in the pockets will gravitate into the runways, and by reason of the inclination of the main and branch runways, the balls gravitate therealong and are finally delivered to a receptacle 37 arranged at the forward end of the table. In this manner the playing balls are automatically returned to the player for replacement upon the playing field.

In each of the branch runways 36 is a pair of electrical contacts 38 suitably insulated from each other and from the runway, and normally spaced apart. These contacts are so positioned in the respective runway that a playing ball deposited in the corresponding pocket or orifice operates to close the contacts and to thereby close the circuit of which the contacts are the terminals. The contacts are such and so positioned as not to impede movement of the playing ball through the runway, the ball momentarily closing the contacts in its passage through the runway. Sufficient to say for the present, the contacts 38

control the operation of a scoring mechanism to register the strikes and outs in accordance with and as determined by dropping of the playing balls into those pockets 18, designated by the letter S, and all of the out pockets. The contacts 38 in the runways communicating with the pockets 18, designated by the numerals 1^b to 4^b inclusive, are employed to control operation of a mechanism for advancing the base-running player members around the bases.

Scoring mechanism

Reference should be had to Figs. 1 and 9 to 12 inclusive in connection with the following detail description of the construction and operation of such mechanism. The scoring mechanism is contained in a housing 39, preferably located on the frame 15 of the table, as illustrated in Fig. 1, the top of the housing being provided with windows 40 having on the glass panes thereof numerals for indicating two strikes and three outs, as indicated by the legends appearing on the top of the housing. By means of the lamps illustrated in Fig. 21 and designated by the same numerals as appearing in the windows 40, the numerals designating the strikes and outs are adapted to be illuminated, it being understood that the housing may be divided interiorly so that the illumination of any one number will not produce an illumination of any of the other numbers. These lamps are provided with separate circuits to be herein-after traced in connection with Fig. 21, and each of these circuits includes a pair of contacts 41 mounted on plates 42 of insulating material, and normally open so that the corresponding lamp is normally extinguished. These strike and out contacts are adapted to be closed to effect illumination of the corresponding lamps by the provision of two control devices. These control devices are substantially identical in construction and operation and, consequently, a description of one will suffice for both.

As illustrated in Fig. 9, the two control devices are arranged side by side, the control device for the strike contacts comprising a bar 43, the opposite sides of which are formed with longitudinally extending tongues 44 adapted to slide within corresponding grooves (not illustrated) on the interior of the housing 39, this tongue and groove mounting providing a means for supporting the bar for longitudinal sliding movement. The bar 43 is urged to the right, as when viewed in Fig. 9, by means of a spring 45 connected to the bar and to the housing 39. Projecting from the upper side of the bar 43 is a pin 46 positioned to successively engage and close the strike contacts 41 under advance movement of the bar 43 from its urged or retracted position. The upper side of the bar is provided with a series of transversely extending

teeth 47 constituting a rack which is adapted to be engaged by a pawl 48 having its upper end bent at an angle to form an armature 49 for an electro-magnet 50. The pawl is slideable in a guide yoke 51, and by means of a spring 52 the pawl is urged out of engagement with the rack teeth 47. Energization of the magnet 50 attracts the armature 49 to move the pawl 48 downwardly against the tension of the spring 52 to engage one of the teeth 47, and then advance the bar 43 one step in which the pin 46 engages the first strike contacts 41 to close the latter and thus illuminate the corresponding lamp. Deenergization of the magnet 50 permits the spring 52 to return the pawl to its normal position so that when the magnet is again energized the pawl will be actuated to advance the bar 43 another step. Thus, the pin 46 passes from the first pair of strike contacts into engagement with the second pair so as to close the latter and thus illuminate the corresponding lamp. Upon a third operation of the pawl 48 the pin 46 passes beyond the last pair of strike contacts 41 so that the control device may be described as being ineffective to register a third strike. However, this is as intended, for at this stage in the operation of the strike control device it is effective to operate the out control device for the reason that upon a third strike being executed by the player an out should be registered. The out control device is, therefore, provided with a lug 53 on the bar 43 which, under the third advance movement of the bar, engages an arm 54 on one end of a shaft 55 which extends to the out control device where it is provided with a pawl 56 that is adapted to engage the rack teeth of the bar for the out control device. In designating the parts of the out control device, I have employed the same numerals as used for corresponding parts of the strike control device but with the addition of the exponent *a*. Under advance movement of the lug 53 the arm 54 is elevated to rotate the shaft 55 and thus cause the pawl 56 to engage a tooth 47^a on the bar 43 to advance the bar one step. This causes the pin 46^a to engage and close the first pair of out contacts 41, thus illuminating the corresponding lamp to register one out. The operation of the pawl 48^a is such that this first advance movement of the bar 43^a to close the first pair of out contacts may be accomplished independently of the strike control device, and in fact the out control device may be operated wholly independently of the strike control device except where it should be operated to register an out by reason of the accumulation of three strikes. The rack 47^a is provided with a sufficient number of teeth to allow the pawl 56 to effect advance movement of the bar 43^a from its normal position as well as from the two succeeding advance positions so that should the out registering mechanism indi-

cate or register one or two strikes, the strike control device upon being moved to its third strike position will effect operation of the bar 43^a to cause registration of an additional out.

In the operation of both control devices, the bar 43 or 43^a is advanced against the action of the spring 45 or 45^a, and, consequently, it is necessary to latch the bars in each of its advanced positions in order that upon a succeeding operation of the pawl 48 or 48^a closing of the contacts 41 will be effected in the intended sequence. The two means for latching the bars 43 and 43^a in advanced position and also in what may be termed the normal or retracted position, are identical; hence, a description of one will suffice for both. I likewise employ like numerals for like parts with the numerals designating the parts of the latching means for the bar 43^a provided with the exponent *a*.

The latching means for the bar 43 comprises a plurality of teeth 57 on the under side of the bar, any one of which is adapted to be engaged by a pawl 58 pivoted to swing about an axis 59 to occupy one position in which it engages the teeth 57 to latch the bar against retrograde movement, and another position in which it is free of the teeth so that the spring 45 is free to return the bar to normal position. These two positions of the pawl are illustrated in Figs. 10, 11, and 12, and to temporarily maintain the pawl in either of these two positions, the pawl body is provided with two surfaces 60 and 61, either of which is engaged by a flat spring 62. The angular relation of these surfaces 60 and 61 is such that the spring coacts therewith to maintain the pawl in either of the two aforesaid positions yet allowing movement of the pawl to or from either of such positions. To move the pawl to the latching position shown in Fig. 10, I provide a tongue 63 on the under side of the bar 43. This tongue is actuated to engage and move the pawl to latching position by retrograde movement of the bar 43 as will be clear from a consideration of Fig. 12. To move the pawl to a non-latching position, I provide a tongue 64 on the spring end of the bar 43 and at the lower side thereof. This tongue 64 engages a projection 65 on the pawl body as the bar 43 is moved to its final advanced position, thereby rotating the pawl to non-latching position as will be clear from a consideration of Fig. 11. Thus, when the bar 43 reaches the final advanced position it is free to be retracted to normal position under the action of the spring 45. As it returns to such position, however, the tongue 63 now operates to engage and return the pawl 58 to latching position under a condition in which the out control device moves into the third out registering position when the strike control device is in either the first or second strike registering position. It is necessary to return the strike control device to the nor-

mal position concurrently with return of the out control device in order that the scoring mechanism may be cleared preceding the start of a new inning or half inning. To take care of this condition, I provide on the tongue 64^a an arm 64^b which extends beneath the bar 43 so as to function the same as the tongue 64, but independently thereof, and to move the pawl 58 to release position as the bar 43^a reaches the third out position, thereby permitting the bar 43 to return to normal position.

Player advancing mechanism

As shown in Fig. 1, the frame 15 of the table is constructed to accommodate an endless belt 66 and a plurality of pulleys about which the endless belt is trained. Four of the pulleys indicated at 67 are arranged at the four corners of the rectangle and constitute idler pulleys. The fifth pulley 68 constitutes a driving pulley and, as shown in Fig. 4, is fixed to the upper end of a vertical shaft 69 with the lower worm 71 on the shaft of an electric motor M. By energizing the motor M, the pulley 68 is rotated to actuate the belt 66 for the purpose of advancing around the bases of the playing field four base-running player members designated as P¹, P², P³, and P⁴, and to be hereinafter referred to as players. These players are mounted equidistantly along the length of the belt 66 in order that when the belt is actuated in the playing of the game any one player will be advanced one or more bases. Each player comprises an L-shaped member 72 secured to the belt 66 by hinged connections 73 so as to permit the member to occupy the upright or active position shown in solid lines in Fig. 8 or the reclined or inactive position shown in dotted lines. The member 72 is adapted to be moved from the inactive to the active position manually, and when in such position the player represented by the member is supposed to be in running position. In the inclined or inactive position of the member, the player represented thereby is assumed to be in a non-running position. For moving the member 72 from the active to the inactive position, I provide an electro-magnet 74, the armature 75 of which is provided with an arm 76 normally urged by a spring 77 to the solid line position shown in Fig. 8, but adapted to be moved to the dotted line position when the armature 75 is attracted by energization of the magnet 74. Such movement of the arm 76 causes it to engage and move the member 72 to inactive position. By reference to Fig. 21 it will be noted that there are only three such magnets 74, one for each of the three bases, the home base being without a magnet for the reason that as the player moves from third to home base while in running or active position, it will be engaged by the tapper of a bell 78 (Fig. 1), and

thrown to non-running or inactive position, the tapper in turn being operated by the player member to sound the bell and thus indicate to the operator that a run has been scored.

5 The three magnets 74 are adapted to be simultaneously and momentarily energized by electrical connection to the third pair of out contacts 41 of the out control mechanism so that when a third out is made all of the magnets will be energized to move the member 72 to inactive position. For this purpose a third contact is added to the aforesaid pair of contacts as will be described hereinafter.

10 Advance movement of the players P^1 , P^2 , etc., around the bases 31, 32, etc., is controlled indirectly by the playing ball falling into those base pockets 18 designated 1^b, 2^b, etc., and directly by the playing ball engaging 20 and closing those pairs of contacts 38 in the runways for the base pockets. These pairs of contacts in turn control circuits for energizing four magnets 79, 80, 81, and 82, which constitute part of a control mechanism for controlling advance movement of the belt 66 in accordance with the base value of the hits 25 scored on the playing field. The belt 66 is shown in Fig. 1 as provided with four pins 83, and each of which operates in a groove 84 in the table frame 15, as clearly illustrated in Fig. 6. It will, of course, be understood that this groove 84 is not continuous, the frame being cut away at one part to accommodate 30 certain parts of the control mechanism, and in order that such parts may have operative engagement with the pins 83. The control mechanism includes a pivoted latch 85 (Fig. 13) located within a housing 86 (Fig. 15) and mounted on a stub axle 87 secured to the 35 housing. A spring 88 is associated with the stub axle 87 and the hub of the latch 85 to yieldably urge the latch into the path of movement of the pins 83 so as to engage any one of the pins and thus latch the belt against 40 further movement. The latch 85 is provided with a head 89 recessed to accommodate the pin 83 and in such manner that it will act as a positive means for engaging the pin to hold the belt against further movement. The 45 latch is provided at its lower end with an extension 90 operable to close a pair of contacts 91 when the latch 85 is moved to a released position with respect to any one pin 83. These contacts 91 constitute the terminals of the 50 circuit for the motor M as will be seen from a consideration of Fig. 21, and, consequently, the motor M will be energized only when the contacts 91 are closed.

55 The latch 85 is adapted to be moved to released position by the provision of an arm 92 pivoted at the point indicated at 93 so that one end of the arm engages the latch 85 while its other end is operatively connected to a lever 94 through a link 95. The lever 94 is 60 fulcrumed at the point indicated at 96. The

lever 94 is situated exteriorly of the housing 86 as will be clear from a consideration of Fig. 15, and further, the table frame 15 is provided with a groove 97 to permit the lever to be moved to a position in which it operates the arm 92 to move the latch 85 to released position. For moving the lever 94, I provide four control units or elements selectively operable to move and maintain the lever 94 in a latch-releasing position for a predetermined period of time in order that the belt 66 may be released and the motor M energized, all for the purpose of advancing the belt predetermined distances to advance the players around the bases, and for a predetermined 70 number of bases. The magnets 79, 80, 81, and 82 constitute parts of the four control units, and as shown in Fig. 13, the several magnets are provided with armatures designated, respectively, 98, 98^a, 98^b, and 98^c. 75 These armatures are pivoted on a rod 99 secured within the housing 86 with their upper ends bifurcated to receive bearing sleeves 100 and pins 101 for pivotally supporting the sleeves on the armatures. Each sleeve rotatably receives the reduced extension 102 of a shaft 103, the shafts for the four units being distinguishable by the exponents of the numeral 103. As shown in Fig. 15, each shaft is rotatable and movable longitudinally 80 in suitable openings of the housing 86, the projecting ends of the shafts being provided with disk-shaped heads 104, 104^a, etc. Coiled springs 105 are associated with the heads 104 and the housing 86 to yieldably urge the shafts 103 in a counterclockwise direction, as when viewed in Fig. 14. The head 104 of the shaft 103 is provided with a single peripheral recess 106, while the other heads 104^a, 104^b and 104^c are provided, respectively, with two, 85 three, and four recesses 106. These recesses are provided for the purpose of accommodating any one of the belt pins 83 and in such manner that as the pin passes across the head it will engage the latter within a recess and thus rotate the corresponding shaft. Of course, the belt pins 83 are normally ineffective to rotate any one of the shafts 103 because the shafts normally occupy what may be termed a retracted position, as illustrated in 90 Figs. 13, 15, and 18, and in which position the heads 104 are out of the path of movement of the belt pins. The shafts are adapted to be moved to an advanced position, in which the heads are in the path of the belt pins through 95 energization of the magnets 79, 80, etc. The energization of any one magnet attracts its respective armature 98, thus moving the shaft 103 longitudinally to advance the head 104 into the path of movement of the belt pins. 100 As the head 104 moves to this advanced position it engages the lever 94, thus moving the latch 85 clear of the pin 83 and closing the contacts 91 to energize the motor. As long 105 as any one shaft 103 remains in advanced position 110

sition, its respective head 104 functions to maintain the latch in released position and the contacts 91 closed. It will be manifest, therefore, that the distance which the belt 66 advances under the action of the motor M depends upon how long any one of the heads 104 remains in advance position. Consequently, in order to advance the belt 66 various distances for advancing the players P¹, P², etc., 10 a predetermined number of bases in accordance with the base value of hits registered by the playing ball, it is necessary that the several shafts remain in advanced position different periods of time to correspond to the 15 four advance movements of the belt 66.

The first control unit comprising the magnet 19 and its corresponding shaft 103 is designed to limit movement of the belt 66 to advancement of a player or players a single base, 20 while the three remaining control units are designed to control movement of the belt to advance the player or players two, three, and four bases, respectively. To effect such functioning of the several control units it is necessary 25 that the respective shafts 103, 103^a, etc. at once be returned to retracted position following rotation thereof in advance position for different periods of time. To this end the shafts 103 are rotated in a clockwise direction by engagement of the belt pins 88 with the shaft heads 104, and for different distances as determined by the number of notches 106 of the heads. Thus, it will be seen that the degree of rotation of the shafts 30 103 increases from the first shaft 103 to the last shaft 103^c. The several shafts are provided with pins 107, 107^a, etc., and which, as clearly illustrated in Fig. 14, are disposed different distances circumferentially of the shafts and from a given point on the circumference. In the instance of the pin 107 for the shaft 103, the shaft, when rotated by engagement of its head with the belt pin elevates the pin 107 into the cam slot 108 of a yoke 109 secured within the housing 86 as shown in Figs. 14 and 15. By reason of the contour of the slot 108 the pin 107 is moved rearwardly in the slot thus moving the shaft 103 longitudinally back to retracted position. As soon 40 as the shaft has returned to retracted position, the pin 107 is in such position within the slot 108 that it can pass freely from the slot so that the spring 105 is now free to rotate the shaft back to normal position. As the shafts of the other units are subjected by the belt pins to two, three, and four rotating impulses, respectively, it is necessary to provide some means for retaining the shafts in advanced position until the final rotating impulse occurs. This means, in the present instance, 45 comprises a circular rack 110 on each shaft 103^a, 103^b, and 103^c. A pawl 111 is pivoted on the yoke 109 to engage the rack teeth 110 and in a manner to retain the shaft against rotation in a counter-clockwise direction.

The pawl 111 is provided with an L-shaped extension 112 which is positioned in respect to the corresponding slot 108 so as to be engaged by the corresponding pin 107^a, etc., and to be lifted by the pin to move the pawl out of engagement with the rack teeth 110 in order that the spring 105 may function to spin the shaft back to normal position. It will, of course, be understood that such movement of the pawl occurs after the pins 107^a, 107^b, or 107^c has retracted the shaft through its engagement with the slot 108. The pawl 111 is urged into engagement with the teeth 110 by means of a spring 113 secured to the yoke 109. However, the pawl 111 is provided with two surfaces 111^a and 111^b angularly arranged, and one of which is engaged by the spring 113 when the pawl is in active position and the other when the pawl is in released position and so as to maintain the pawl in such released position. It is, of course, necessary that the pawl 111 be returned into engagement with the teeth 110 after the shaft has returned to normal position in order that the shaft may be held in its different circumferential positions when operated a second time. This is accomplished by the provision of a lug 114 on the periphery of the shaft 103^a, 103^b or 103^c, which is so positioned that as the shaft rotates back to normal position it engages the upper side of the pawl and moves the latter down into engagement with the teeth 110. This operation will be clear from a consideration of Figs. 19 and 20 and, as here shown, the under side of the yoke 109 is recessed as indicated at 115 to accommodate the lug 114 so that the lug will not interfere with longitudinal movement of the shaft as will be understood.

Operation

In describing the operation of the game apparatus, I will refer to Fig. 1 and the electrical circuit diagram illustrated in Fig. 21 in the belief that the construction and operation of the main parts of the apparatus is understood from the preceding description. In Fig. 1, the playing field 16 is shown provided with a positioning line 116 for designating the starting position of the object ball 117 and which ball constitutes one of the playing balls. The other playing ball indicated at 118 is what may be termed a cue ball, as distinguished from the object ball 117 in that the former is designed to be projected over the playing field by the use of the cue, such as that employed in the playing of pocket billiards. The cue ball 118 should be positioned on the playing field adjacent the homeplate 31, as is illustrated in Fig. 1. With the two playing balls positioned as described, and the scoring and player advancing mechanisms in normal and non-registering positions, the game is now ready for play.

The object of the game is, of course, to project the cue ball 118 against the object ball 117 so as to project the latter into the hit pockets 1^b, 2^b, etc., the success of the operator in this respect depending upon the skill with which he avoids the object ball being projected into the strike and out pockets. Should the operator project the object ball into one of the hit pockets say, for example, 10 one of the one base hit pockets, the corresponding pair of contacts 38 will be closed by the object ball thus momentarily energizing the magnet 79 and through the following circuit: From positive side of battery B 15 through wires 119 and 120, winding of magnet 79, main wire 121, branch wire 122 to one of the contacts 38, and from the latter through the other contact, then through branch wire 123, and main wires 124 and 125 20 back to the negative side of the battery. The resultant energization of the magnet 79 actuates the corresponding control unit to move the shaft 103 to advance position to actuate the latch 85 and the contacts 91 to release 25 the belt 66 and energize the motor M so that the belt is now set into operation. In the manner previously described, the first control unit functions to permit the belt 66 to move for a distance corresponding to the distance 30 from the home plate 31 to first base 32, and where the player P¹ or P² has been manually moved to active position, the belt in its movement will advance this player from home plate to first base. Concurrently with 35 this operation, the motor M drifts until the belt 66 has been moved to cause the next pin 83 in the rear to abut the latch head 89 when further movement of the belt is checked so that the corresponding player is held at first base.

40 From a consideration of Fig. 21, it will be clear that closure of any of the pairs of contacts 38 of the one base hit pockets will operate the player advancing mechanism in the manner just described by reason of the fact that I have provided each pair of contacts 38 with branch wires 122 and 123 that are connected respectively to the main wires 121 and 124. Thus, each time a one base hit is 45 scored the players will be advanced one base about the playing field.

50 Should the object ball 117 be deposited in any one of the two base hit pockets the corresponding pair of contacts 38 will be closed 55 to energize the magnet 80 through the following circuit: From wire 121 to wire 126, winding of magnet 80, main wire 127, branch wire 128, contacts 38, and branch wire 129 to main wire 124 from whence the circuit may 60 be traced through main wire 125 back to battery. Energization of magnet 80 operates the second control unit to cause operation of the belt 66 to advance the player or players two bases instead of one. It will be understood 65 that when a second player is put into

action the operator lifts the player member to active position, thus the operator can at all times observe just what players are in action, as it will be appreciated that all the players are subject to advancement when the 70 belt 66 is moved. From a consideration of Fig. 21, it should be clear that the circuits or any one of the other pairs of contacts 38 for the two base hit pockets is the same as that described in connection with the first 75 two base hit pockets as all of these contacts are provided with branch wires 128 and 129 connected, respectively, to the main wires 127 and 124. Thus, when the contacts are closed for any one of the two base hit pockets, the 80 magnet 80 will be energized to operate its respective control to advance the players two bases. When the object ball is deposited in any one of the three base hit pockets, the 85 magnet 81 is energized to operate its respective control unit for advancing the players three bases. The circuit for the magnet 81 may be traced as follows: From wire 126 to main wire 130, branch wire 131, contacts 38, branch wire 132, main wire 124, back to 90 battery. Similarly, the contacts 38 for all other three base hit pockets are provided with branch wires 131 and 132 which are connected respectively to the main wires 130 and 124. Thus, when any of these contacts are 95 closed the belt will be actuated to advance the players around three bases.

Should the object ball be deposited in any one of the four base hit pockets the magnet 82 is energized to operate its respective control unit and thereby cause the belt 66 to advance the players around all the bases or, in other words, from home plate around the three bases back to home plate. The circuit for the magnet 82 may be traced as follows: 100 From wire 126 through winding of magnet 82, main wire 133, branch wire 134, contacts 38, branch wire 135, and main wire 124 back to battery. The other pair of contacts 38 for the remaining four base hit pockets are likewise provided with branch wires 134 and 135 which are connected, respectively, to main wires 133 and 124 so that when these contacts are closed the magnet 82 will be energized to likewise operate the respective control 110 unit to advance the players four bases.

Where the object ball is deposited in any one of the out pockets 21, the respective pair of contacts 38 will be closed by the ball to energize the magnet 50^a to operate the pawl 48^a 120 and thus advance the bar 43^a one step to cause closing of the first pair of out contacts 41. The circuit for the magnet 50^a may be traced as follows: From positive side of battery B through wires 119 and 136, winding magnet 125 50^a, wires 137 and 138, contacts 38 and wire 139 to main wire 124, and back to battery through wire 125. By extending the wire 137 to the contacts 38 for the other three out pockets, and then connecting the contacts to 130

the main wire 124 in the manner illustrated in Fig. 21, it should be manifest that with closing of any pair of contacts 38, the out magnet 50^a will be energized to actuate the pawl 48^a. Initially, energization of the magnet 50^a by closing any one pair of contacts for the out pockets advances the ball 43^a one step to close the first out pair of contacts 41. Such closure of the contacts 41 illuminates the first out lamp to register one out. The circuit for this lamp may be traced as follows: From wire 136 through the aforesaid lamp, wire 140, contacts 41, wires 141 and 125 back to battery. To register the second and third outs it is, of course, necessary to reenergize the magnet 50^a to advance the bar 43^a the remaining two steps whereby the other two out lamps are successively illuminated. It is believed that the circuit for these two lamps will be obvious from a consideration of Fig. 21. Upon closing of the third pair of out contacts 41 one of the contacts engages a third contact 142 illustrated in Figs. 9 and 21. This contact 142 controls the circuits for the magnets 74, and when such magnets are energized the member 72 will be thrown to a reclined position on the belt 66 to cause the players represented thereby to occupy non-running or inactive position. By tracing the circuit for one of the magnets 74 it will be clear that upon closure of the contact 142 all the magnets are simultaneously energized to move all the players to inactive position. The circuit for one magnet 74 is as follows: From contact 142 through wires 143 and 144, winding of magnet 74, wire 145, to main wire 124 and back to battery through wire 125. From the preceding operation it will be clear that when the out mechanism registers the third out, any player occupying active position will be automatically moved to inactive position, thus clearing the bases of the playing field and conditioning the apparatus for the beginning of a new inning or half inning.

The magnet 50 for actuating the strike scoring mechanism is electrically connected to all of the pairs of contacts 38 of the strike pockets so that when any one pair of contacts is closed by the playing ball, the magnet will be energized to actuate the pawl 48 and thus advance the bar 43. Initially, closure of any one pair of contacts 38 causes the pawl 48 to advance the bar 43 one step. As a result, the first pair of strike contacts 41 is closed, thus supplying current to the first strike lamp from the battery B and thereby illuminating the latter to register one strike. The circuit for the magnet 50 may be traced as follows: From wire 136 to wire 146, winding magnet 50, main wire 147, branch wire 148, contacts 38 of any one strike pocket, branch wire 149 to main return wire 124. The circuit for the first strike indicating lamp is from wire 136 through wire 150 to

the respective pair of contacts 41, and from the latter through wire 151 to wire 125.

Upon closure of a second pair of contacts 38 for any one of the strike pockets, the magnet 50 is again energized to cause closing of the second pair of strike contacts 41, and through such closure illuminating the second strike lamp to register the second strike. The circuit for the second lamp is from wire 136 to wire 152, contacts 41, and wire 153 to wire 151. With closure of a third pair of contacts 38, the magnet 50 is again energized to further advance the bar 43 and thus operate the pawl 56 to cause the out scoring mechanism to register an out, as has been previously described. Movement of the bar 43 to this final position effects automatic release of the pawl 58 so that the bar is returned to normal position under the action of the spring 45. Similarly, the bar 43^a, upon movement to a position in which the pin 46^a is beyond the third pair of contacts 41, effects automatic release of the pawl 58^a so that the bar 43^a is returned to normal position by the corresponding spring. Thus, the two mechanisms are automatically returned to normal positions following the sequence of operation previously described.

Although I have herein shown and described a game apparatus involving the employment of mechanism for actuating the belt 66 to advance the players around the bases in accordance with the base value of hits scored, it is to be understood that my invention contemplates the provision of less expensive form of game apparatus in which the aforesaid mechanism may be dispensed with and the belt moved manually to advance the players.

I claim:

1. In a game apparatus, a playing field having bases thereon and ball-receiving orifices therein adjacent the edges of the playing field and other orifices spaced from the first and remote from the edges of the playing field, ball-deflecting objects positioned about the other orifices, runways in communication with all of said orifices, base-running player members, mechanism for advancing said members around the bases of the playing field, score registering means, and means disposed in said runways and operable by a ball deposited therein through said orifices for controlling actuation of said mechanism and registering means.

2. In a game apparatus, a playing field having ball-receiving orifices, ball-deflecting objects movable on the field about certain of said orifices, score registering means, and control devices positioned with respect to said orifices so as to be operable by balls deposited therein for controlling actuation of said registering means.

3. In a game apparatus, a playing field

- having bases, a ball cushion surrounding the field, orifices within the playing field adjacent the ball cushion, base-running player members movable in paths exteriorly of the ball cushion, mechanism for advancing said members around the bases, score registering means, and control devices positioned with respect to said orifices to be actuated by balls deposited in the orifices to control operation of said mechanism and registering means.
4. In a baseball game apparatus as embodied in claim 2 wherein other orifices are provided within the playing field, and ball-deflecting objects are mounted for movement about said orifices, said other orifices having devices for controlling actuation of the "out" registering part of said registering means.
5. In a game apparatus, a playing field having ball-receiving orifices therein and conical entrances for the orifices, rotatable frames on the playing field, one for each of said entrances and rotatable about the corresponding orifice, and ball-deflecting objects carried by said frame.
6. In a game apparatus, a playing field having ball-receiving orifices therein and conical entrances for the orifices, rotatable frames on the playing field, one for each of said entrances rotatable about the corresponding orifice, and balls carried by said frame and rotatable about their own axes.
7. In a baseball game apparatus, a playing field having bases and ball-receiving orifices therein, base-running player members, mechanism for advancing said members around the bases, said members being pivoted on said mechanism to occupy two extreme positions, score registering means, control devices positioned with respect to the orifices to be actuated by balls deposited in the orifices to control operation of said mechanism and registering means, and means for moving said members to one extreme position, said means being connected to the registering means so as to be operable when the registering means registers three "outs."
8. In a baseball game apparatus, a playing field having bases, base-running player members, mechanism for advancing the players around the bases comprising an endless belt upon which said members are mounted, a motor for driving the belt, means for controlling movement of the belt by said motor comprising projections on the belt, a latch engageable with any one of the projections for controlling movement of the belt, a switch for controlling the motor connected to said latch to be operable thereby in a manner to close the switch when the latch is out of engagement with a projection, and an electro-magnetic means for operating the latch to disengage the projection and close said switch.
9. In a baseball game apparatus, a playing field having bases, playing balls, means for projecting the balls over the playing field, an endless belt having thereon members representing base-running players, a motor for operating the belt to cause said members to advance around the bases, and means controlling operation of the motor comprising projections on the belt, a latch urged to a position in which it is disposed in the path of movement of the projections so as to coact therewith in securing the belt against movement, a switch for the motor operable by the latch, a plurality of elements operable to move the latch out of the path of movement of the projections and to simultaneously close said switch for progressively increasing periods of time to move the base-running player members different distances around the bases, and means operable by the playing balls for actuating respective elements in response to "hits" of different base values whereby said members are advanced a number of bases corresponding to the base value of each "hit."
10. In a baseball game apparatus as embodied in claim 9 wherein the said members are movable on the belt to occupy either of two extreme positions, score registering means operable by the playing balls, and means for moving said members to one extreme position when the registering means registers the end of a "half inning" or "inning."
11. In a baseball game apparatus, a playing field having bases, playing balls, means for projecting the balls over the playing field, and endless belt having thereon members representing base-running players, a motor for operating the belt to cause said members to advance around the bases, means controlling operation of the motor comprising projections on the belt, a latch disposed in the path of movement of the projections and adapted to engage any one of the projections to limit movement of the belt, a switch for the motor normally open but adapted to be closed when the latch is moved out of the path of movement of the projections, a plurality of rotary elements having notched heads, said elements normally occupying a position in which the heads are disposed out of the path of movement of the projections, electro-magnets for moving the elements so that their heads will be disposed in the path of movement of the projections, the notches of said heads progressively increasing in number, respectively, to provide a corresponding number of teeth engageable by the projections for rotating the elements, means for latching the elements in the position to which they have been rotated by said projections, means for releasing the last means after the elements have reached their final rotative position, and means operable by the playing

balls for actuating the electro-magnets in response to "hits" of different base values whereby said elements are moved to position their heads in the path of movement of the projections to activate said latch and close said switch for predetermined intervals so as to advance said members around the bases to correspond to the base value of each "hit."

12. In a game apparatus, a playing field, an endless belt having members thereon in representation of base-running players, said members being pivotally mounted on the belt to occupy elevated and lowered positions, playing balls adapted to be projected over the playing field, and means operable by the playing balls for simultaneously moving all of said members to the lowered position.

13. In a baseball game apparatus, a playing field, a playing ball adapted to be projected over the field, electrical switches normally open but adapted to be closed by the playing ball, and "strike" registering mechanism comprising a rack bar, a projection on the rack bar, switches in the path of movement of the projection so as to be successively closed by said projection under advance movement of the rack bar, means for urging the rack bar to a retracted position, means for advancing the rack bar in a step-by-step movement to cause the projection to successively close said switches, said means being operable by closing of any one of the first switches, and means for latching the rack bar in any one of its advanced positions and for releasing the rack bar to permit it to return to retracted position.

14. In a baseball game apparatus, a playing field, a playing ball adapted to be projected over the field, electrical switches normally open but adapted to be closed by the playing ball, and "strike" registering mechanism comprising signals, contacts for controlling the signals, a rack bar, a projection on the rack bar for closing the contacts, and means controllable by any one of said switches for advancing the rack bar from a retracted position and in a step-by-step movement to cause said projection to successively close said contacts.

15. In a game apparatus, a playing field, a playing ball adapted to be projected over the field, electrical switches normally open but adapted to be closed by the playing ball, a rack bar, means for urging the rack bar to a retracted position, means for latching the rack bar in any one of the advanced positions, and means for releasing the rack bar following a prescribed number of advance movements to permit it to return to retracted position under the action of said urging means.

16. In a baseball game apparatus, a playing field, a playing ball adapted to be projected over the field, electrical switches normally open but adapted to be closed by the

playing ball, and an "out" registering mechanism comprising three signals, contacts for each of the signals normally open, a bar, a projection on the bar for closing said contacts, electro-magnetically operated means for moving said bar in a step-by-step movement to cause said projection to successively close said contacts, and means for latching the bar in each of its advanced positions.

17. In a game apparatus, a playing field, a playing ball adapted to be projected over the field, electrical switches normally open but adapted to be closed by the playing ball, and score registering means comprising a plurality of signals, contacts for actuating the signals, a bar, a projection on the bar for closing said contacts, means for urging the bar to a retracted position, means for advancing the bar in a step-by-step movement corresponding to the spacing of said contacts to cause said projection to successively close said contacts and thus successively operate said signals, means for latching the bar in each of its advanced positions, means for releasing the latch means following closing of all of said contacts to permit the bar to be restored to retracted position by said urging means, and means operable by the bar for restoring the latching means to latching position as the bar returns to retracted position.

18. In a game apparatus as embodied in claim 17 wherein the means for advancing the bar comprises a pawl and an electro-magnet for actuating the pawl, said magnet being connected to all of said switches so as to be energized with closing of any one of the switches.

19. In a baseball game apparatus, a playing field, a playing ball adapted to be projected over the field, electrical switches normally open but adapted to be closed by the playing ball, a "strike" registering mechanism and an "out" registering mechanism, said registering mechanism each comprising a plurality of signals, contacts for the signals normally open, a bar urged to a retracted position, a projection on the bar for closing the contacts to actuate the signals, means for advancing the bar in a step-by-step movement to cause the projection to successively close the contacts, means for latching the bar in any one of the advanced positions to maintain the corresponding contact closed, the means for advancing the bar for the "strike" registering mechanism being operable by closing of certain of said switches and the means for advancing the bar of the "out" registering mechanism being operable by closing of the remaining switches, means for actuating the latching means to release the bars so that they may be returned to retracted positions, and means operable by advance movement of the "strike" bar for advancing the "out" bar whereby when the "strike" registering mechanism moves to a third

"strike" registering position the "out" bar will be advanced to actuate one of the signals of the mechanism and thus indicate an "out."

Signed at Los Angeles, in the county of
5 Los Angeles and State of California, this 15th
day of November, A. D. 1928.
